Primary Examiner — Paula Allen Greene(74) *Attorney, Agent, or Firm* — Young & Thompson(57) **CLAIM**

The ornamental design for a headphone, as shown and described.

DESCRIPTION

FIG. 1 is a perspective view of front, top and right side of a headphone device showing my new design;
 FIG. 2 is a perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view in an alternate state thereof;

FIG. 10 is another view in an alternate state thereof; and,

FIG. 11 is another view in an alternate state thereof.

The broken lines form no part of the claimed design.

1 Claim, 10 Drawing Sheets(56)
